[57] ABSTRACT

This invention discloses a device for laying out and measuring the length of draperies and pressing in crinoline fabric, wherein the floor area taken up by the device is a small fraction of the area of the drapery.

The device has a horizontal planar working table or surface about 2 feet wide and any convenient length. On the back long side of the working surface, a vertical means is disposed to define a vertical surface intersecting the working surface, preferably at right angles. The vertical means has at least two spaced endless chains, each engaging a sprocket located a convenient distance above the working surface and each engaging another sprocket disposed therebelow, so that each chain has a portion that moves vertically substantially within the vertical surface. The chains are moved at the same speed, both up and down, by suitable means. To both chains a clamping bar is secured to move up and down therewith, and parallel with the working surface. The clamping bar has means for securing the hemmed straight edge of a piece of cloth, so that the cloth is lifted thereby with its lower portion resting on the working surface. When the straight edge is given height above the working surface, a keeper rod is laid at the apex of the formed right angle to steady the cloth so that it can be measured, cut and hemmed at the required dimension. Preferably, the keeper rod is mounted to rotate about a horizontal axis located below the table, so that the bar is stowed conveniently when not in use.

DEVICE FOR TABLING LENGTH OF DRAPERIES

FIELD OF THE INVENTION

This invention relates to a tabling device whereon a drapery can be trimmed, measured for length and crinoline fabric pressed in along one straight edge and, more particularly, to such a device that is compact, easy to operate, and allows one to operate on the drapery with minimum handling.

BACKGROUND OF THE INVENTION

When cloth, such as drapery cloth, is to be hemmed at opposite edges so that the edges are apart a predetermined distance, the drapery panels of cloth are first cut to approximate lengths from the bolt, allowing for additional material, to allow one to form the hems. The panels are sewed together and three hems are formed and sewed along three edges. The fourth hem, on the opposite edge should now be formed and sewed. If the width between opposite hems is to be about 8 feet in height, the cloth is placed on a flat tabling device and one hemmed edge is held fast by convenient means. The opposite unhemmed edge is measured to the proper length and the hem is formed of the proper length with the crinoline fabric pressed in place. The hem is held in place by pinning until sewed on a sewing machine. This is a relatively simple operation. However, when one tries to do it on a commercial scale, time is of the essence. Up to now, tabling devices were formed with a clamping bar disposed at one end. The 25 clamping bar has a moveable rod that comes in contact with a fixed plate so that the hemmed edge is disposed therebetween. The rod and plate are pressed together by well known means, such as, springs and eccentric cams.

However, this prior art table or tabling device has one drawback in that the size of the table should be at least the size of the cloth or drapery. If it is not, then only a portion or a fraction of the cloth can be hemmed and pinned at a time. When one attempts to make draperies, having a width of, for example, 40 feet long, require many hemming and shifting operations. If one expects to lay out, measure and pin the hem in one operation, the table should be at least 40 feet long and the height of the drapery. This is uneconomical because an average drapery shop will find that this table is unusually oversized for the usual requirement of drapery sizes. Therefore, up to now, most drapery layout tables were made about 5 feet wide and about 10 feet long, so that drapes up to 10 feet in length could conveniently be made by hemming and shifting the cloth 5 feet at a time.

SUMMARY OF THE INVENTION

Briefly, my invention includes a means for lifting, vertically, the hemmed lower edge of a drapery cloth to a predetermined height. A narrow, horizontal working table or surface is disposed below the cloth, with the unravelled edge of the hem resting on the table. Another means includes a rod which is provided to rest on the cloth and, in turn, on the table, and is disposed at a position so that when the portion of cloth adjacent the unravelled edge is laid smooth on the table, the cloth forms a right dihedral angle. The rod holds the cloth steady. Preferably, the means for lifting includes at least two endless chains, each having a pair of

sprockets, one sprocket over the other. The chains carry a clamping bar which moves up and down while in a horizontal position. The clamping bar has means for clamping the hemmed edge of the drapery and lifting it. The means that includes the rod has, in addition, at least two substantially semicircular bent bars welded to the rod and each semicircular bent bar is formed integral with a radially directed bar that is mounted for rotation about a horizontal axis located below and 10 aligned with the working table.

OBJECTS OF THE INVENTION

An object of this invention is to provide a tabling device wherein a section of cloth having one hemmed edge can be conveniently laid out, measured and hemmed along the opposite edge in one operation, and the floor area on which the table rests is a fraction of the total area of the cloth section.

Another object of this invention is to provide a tabling device with means for raising vertically the hemmed edge of a section of cloth above the working surface and with means for keeping the cloth substantially at a right dihedral angle with one surface of the cloth resting on the table.

Another object of this invention is to provide a tabling device with a narrow working surface and with endless chain means disposed on the back side thereof for raising and lowering a clamping bar for clamping therein the hemmed edge of the cloth.

Another object of this invention is to provide a clamping bar for the above object wherein pneumatic means are provided to clamp the hemming edge.

Another object of this invention is to provide a means for the clamping bar of the two previous objects that causes the bar to rotate 90° about a horizontal axis when the bar is lifted off the working table and when returning to the working surface.

These and other objects and features of advantage will become apparent after studying the following description of the preferred embodiment of my invention, together with the appended drawings.

BRIEF DESCRIPTION OF THE DRAWINGS

FIG. 1 is a pictorial view of my novel device wherein the section shown is repeated as many times as is required.

FIG. 2 is a transverse elevation and section of my novel device, shown in FIG. 1.

FIG. 3 is an enlarged section of the clamping bar when positioned on the working surface.

FIG. 4 is an enlarged pictorial in greater detail in the region where the clamping bar is secured to the endless chains.

FIG. 5 shows an elevation in section of the clamping bar of FIG. 4 being raised or lowered to the working surface.

FIG. 6 shows another view of the clamping bar.

FIG. 7 is another transverse elevation, similar to FIG. 2, but showing the drapery cloth suspended from above the table and the keeper means position before the other edge is hemmed.

DETAILED DESCRIPTION OF THE DRAWINGS

Referring to FIG. 1, my novel device is shown pictorially and disposed against a wall 11. The wall 11 and my device extend any required length, as will become apparent hereinafter. A nominal length for my device

would be 40 feet, as this is about the maximum width in which draperies are required to be made. Vertically disposed against the wall 11 are a plurality of spaced channel-shaped uprights 12 and 12a, extending from a floor 13 to a ceiling 14. The uprights are spaced a convenient distance apart, for example, 10 feet. Within each upright 12 is disposed an endless chain 16, each mounted on an upper sprocket 17 and a lower sprocket 18, more clearly shown in FIG. 2. The upper sprockets 17 are bearing mounted individually on axles 21, while the lower sprockets 18 are all keyed to rotate with a shaft 22. Suitable pillow bearings 23 are provided between the shaft 22 and uprights 12 to allow the shaft 22 to rotate. Rotation of the shaft 22 is caused by an electric motor 25 and gearbox 26, as shaft 22 passes through gearbox 26. In FIG. 2, the shaft 22 is shown to be schematically coupled by line 26a to the gearbox 26. Suitably fixed to each upright 12 is a bracket, such as bracket 27, which horizontally supports a working surface or panel 28, which, being like a counter-top, extends about 2 feet from the wall 11, which is sufficiently narrow to allow an operator to reach the back edge, if necessary. To each chain 16 is fixed a clamping means 29 in the form of an elongated bar extending the length of the working surface 28.

Referring to FIGS. 3, 4, and 5 the clamping means 29 and the method for attaching it to the chains 16 is shown in detail. To a convenient link in the chain 16 there is mounted a pad 31 in a convenient manner. The pad 31 has an ear 32 extending therefrom to which is pin-connected a U-link 33. Each U-link 33 is suitably welded to a standard extruded section having a clamping surface or plate 34 and a boxlike stiffener 35. Another extruded section 36 completes the boxlike structure. These extruded sections are well known in the art. On the top of section 35, as viewed in FIG. 3, a plurality of brackets 38 are bolted, as shown, and in this embodiment each has a double bend as it extends over the surface 34. On each bracket 38 is mounted a standard air cylinder 39 having a piston 41 protruding through a hole 42 formed in each bracket 38. Each piston 41 is fixed to a pressing bar 43 of standard shape and size, having a suitable foam surface 44 thereon for gripping cloth, as will become apparent hereinafter. The pressing bar 43 moves in both directions, as indicated by a double-headed arrow 47, whenever the air cylinders are activated or deactivated, respectively. For convenience, the pressing bar 43 is made in about 5-foot sections and therefore the air cylinders connected to that particular section are activated in unison with one air control (not shown). As will become apparent hereinafter, the smaller sections of the pressing bar 43 allow one operator, alone, to secure a portion of the cloth at a time, such as cloth 45 (FIG. 2), in the clamping means, thereby preventing the need of multi-operators. The clamping means 29 has bolted, in addition, on the boxlike stiffener 35, an angle bracket 46 wherein the arm extending upward (FIG. 3) therefrom is connected to, for example, a nylon rope 49 depended from the ceiling 14. The function of the rope 49 will hereinafter be explained.

The device is operated as follows: With the clamping means 29 in the position as shown in FIG. 2, the drapery or cloth 45 that is folded on the floor 13 is lifted up by its hemmed edge 51 and pulled across the working surface 28 in the direction of the arrow 52 until the edge 51 is between the pressing bar 43 and clamping

surface 34, as shown by the dash lines. Since the bar 34 is of a convenient length, only one person is needed to hold the cloth 45 in place with one hand while the other hand activates the air valve (not shown) to cause the bar 43 to bear against the edge 51. This is repeated until the full width of the drapery is clamped, as shown in FIG. 3. Air pressure is maintained so that a firm grip is had on the cloth. The motor 25 is started and it, in turn, activates the gearbox 26 so that the shaft 22 is made to rotate clockwise, as viewed in FIG. 2. This causes the sprockets 18 to rotate and chain 16 to move. The pad 31 secured thereto rises the U-link 33 and in turn the boxlike stiffener 35. The stiffener 35 first rotates downward, counter-clockwise, as viewed in FIG. 2, until the clamping surface 34 is vertical, and then it rises straight, lifting the drapery or cloth 45, as shown in FIG. 1. When the clamping means 29 rises a sufficient height, a means including a keeper rod 54 is positioned, as shown in FIG. 7, so that the cloth forms a right angle or a right dihedral angle. The rod 54 is preferably square, for obvious reasons, although it could be round. To insure freedom of movement, the working surface 28 is spaced a slight amount from the upright 12, as shown in FIGS. 2 and 7, and the rear edge of surface 28 is provided with a vertical ledge 56 so that the rod 54 rests thereagainst with the cloth in between. In order that the rod 54 can be conveniently handled, because relatively long sections thereof are preferred, although not the full length of my layout table, I have provided means to allow the rod 54 to pivot about an axis 57 that is disposed below the working surface and aligned therewith, as shown in FIGS. 2 and 7. FIG. 2 shows the rod 54 pivoted to the forward edge of the surface 28. The means includes more than one substantially semi-circular bent bar 61, wherein one end of each is welded the respective end of the rod 54 and each of the other ends is bent to form radial bars 62. Each other end of bar 62 is made to pivot about axis 57 by standard convenient means 63. Now only one skilled person can form a hem 64 in the edge of the cloth (FIG. 7) in a standard manner. After the hem 64 is formed and pinned, and the rod 54 is pivoted out of the way to the position shown in FIG. 2, the clamping means 29 is lowered. Now, when the clamping means 29 approaches the table, the surface 34 should be horizontal so that the next drapery can be reclamped in place. This result is accomplished by the rope 49, mentioned above, and the angle bracket 46. Referring to FIG. 5, when the clamping means 29 is about the position as shown by the full lines before it comes to rest on surface 28, the rope 29 becomes taut, thereby preventing the top end of the angle bracket 26 from further dropping. The clamping surface 34 is normal to surface 28. As the chain 16 moves pad 31 downward, the clamping means 29 has to rotate to a position indicated by 29a and then by 29b to end up in the position shown by the dash lines 29b adjacent the surface 28, with the clamping surface 34 parallel to surface 28.

Having described the preferred embodiment of my invention, one skilled in the art can devise other embodiments without departing from the spirit and scope of my invention after studying the above description. Therefore, my invention is to be considered limited only to the appended claims and not to the above preferred embodiment.

I claim:

1. A layout table for laying out and measuring cloth comprising:

a working table means forming a surface disposed substantially horizontal;
first means for lifting vertically said cloth on one edge thereof so that said cloth depends to said surface and has a portion resting on said surface; and
second means for forming and holding a dihedral angle in said cloth, with one surface of said cloth held in the plane of said surface of said table means while the other surface of said angle depends vertically.

2. The table of claim 1 wherein said first means for lifting comprises:

a clamping means for gripping said cloth on said one edge;
a plurality of endless chains disposed along one edge of said working table;
an overhead sprocket engaging each chain and disposed above said working table;
another sprocket engaging each chain and disposed below said working table;
a drive shaft coupled to said sprockets for rotating said sprockets in unison; and
said clamping means being fixed to said chains, to cause said clamping means to raise the edge of said cloth horizontally.

3. The table of claim 2 wherein said clamping means comprises:

a box-like elongated member with a flat clamping plate protruding therefrom for the length thereof, and shaped so that said clamping plate is capable of lying flat on said horizontal surface;
at least one pressing bar;
third means for supporting said bar over said clamping plate and for moving said bar towards said clamping plate.

4. The table of claim 3 wherein said third means comprises at least two cylinder and piston assemblies, with each cylinder fixed to said box-like elongated member, and each piston fixed to said clamping bar.

5. The table of claim 1 wherein said working table means comprises:

a long, narrow, rectangular panel disposed substantially horizontal;
a plurality of rigidly fixed structural uprights disposed and spaced along one of the longer back edges of said panel;
fourth means for cantilevering supporting said panels from said upright.

6. The table of claim 5 wherein said second means comprises:

at least one keeper rod; and
fifth means for supporting said keeper rod to rotate about an axis disposed below said panel and aligned with the longer edges thereof.

7. The table of claim 6 wherein said fifth means comprises:

at least two substantially semicircular bent bars, each end having one end fixed to said keeper rod; and
at least two radial bars, each fixed by one end to the other end of said respective semicircular bent bars.

8. The table of claim 1 wherein said working table means comprises a long, narrow, rectangular panel disposed substantially horizontal;

a plurality of rigidly fixed channel-shaped structural uprights disposed and spaced along one of the longer back edges;

fourth means for cantilevers supporting said panel from said uprights.

9. The table of claim 8 wherein said first means for lifting comprises:

a clamping means for gripping said cloth on said one edge;
a plurality of endless chains disposed along one edge of said working table;
an overhead sprocket engaging each chain and disposed above said working table;
another sprocket engaging each chain and disposed below said working table;
a drive shaft coupled to each of said other sprockets for rotating said other sprockets in unison;
said clamping means being fixed to said chains to cause said clamping means to raise said edge on said cloth horizontally.

10. The table of claim 9 wherein said clamping means comprises:

a box-like elongated member with a flat clamping plate protruding therefrom for the length thereof and shaped so that said clamping plate is capable of lying flat on said working table;
a plurality of pressing bars in alignment with each other;

third means for supporting said bars over said clamps and for moving each bar independently of the other bars toward said clamping plate.

11. The table of claim 10 wherein said second means comprises:

at least one keeper rod; and
fifth means for supporting said keeper rod to rotate about an axis disposed below said panel and aligned with the longer edge thereof.

12. The table of claim 11 wherein said fifth means comprises:

at least two substantially semicircular bars, each having one end fixed to said keeper rod and at least two radial bars, each fixed by one end to the other end of said respective semicircular bars.

13. The table of claim 5 wherein said first means for lifting comprises a clamping means for gripping said cloth on said one edge;

a plurality of endless chains disposed along one edge of said working table;
an overhead sprocket engaging said chains to dispose above said working table;

another sprocket engaging each chain and disposed below said working table;

a drive shaft coupled to each other sprocket for rotating said other sprocket in unison;
said clamping means being fixed to said chains to cause said clamping means to raise said edge of said cloth horizontally.

14. The table of claim 13 wherein said clamping means comprises:

a box-like elongated member with a flat clamping plate protruding therefrom for the length thereof, and shaped so that said clamping plate is capable of lying flat on said working table;
a plurality of pressing bars in alignment with each other;

third means for supporting said bars over said clamping plate and for moving each bar independently of the other bars toward said clamping plate.

15. The table of claim 14 wherein said third means comprises at least two cylinder and piston assemblies, 5 with each cylinder fixed to said box-like elongated member, and each piston fixed to a respective clamping bar.

16. The table of claim 2 wherein: 10
said clamping means has a flat clamping narrow plate

extending the length of said table; and pivotal means are provided to cause said narrow plate to rotate from a position parallel to said horizontal surface to a position normal thereto when said clamping means is lifted and to cause said narrow plate to rotate from the normal position to the parallel position when said clamping means are lowered to said horizontal surface.
